UNITED STATES PATENT OFFICE.

NELSON WHITE, OF ITHACA, NEW YORK, ASSIGNOR TO PETERS MORSE MANUFACTURING COMPANY, OF NEW YORK, N. Y., A CORPORATION OF NEW YORK.

PAPER HOLDER FOR ADDING MACHINES.

Application filed September 13, 1923. Serial No. 662,456.

To all whom it may concern:

Be it known that I, NELSON WHITE, a citizen of the United States, and residing in Ithaca, Tompkins County, State of New York, have invented an Improvement in Paper Holders for Adding Machines, of which the following is a specification.

This invention relates to adding machines, and has particular reference to a carriage 10 and paper roll holder therefor, and contemplates certain improvements to the carriage disclosed in Patent 1,386,021 dated August 2, 1921, Heber C. Peters.

While the device shown and described in 15 the above mentioned patent has been found satisfactory in use, the specific mounting of the roll holder has been found more or less inconvenient since it is necessary to move the roll holder in case a wide paper is desired to be used.

It is therefore one object of the present invention to provide roll holding means associated with the carriage whereby rolls of varying widths may be employed, as desired.

25 A further object of the invention is to provide an improved means for mounting the roll holder supporting arms.

Another object of this invention is the provision of adjustable ears for guiding the 30 sides of the paper roll.

Other objects and advantages of this invention will be apparent from the following description taken in conjunction with the accompanying drawings which illustrate the 35 preferred embodiment of the invention and in which:

Figure 1 is a front elevation of the adding machine carriage and its associated roll holder;

40 Figure 2 is a rear elevation of the adding machine carriage and its associated roll holder;

Figure 3 is a right side elevation of the carriage;

45 Figure 4 is a left side elevation of the carriage;

Figure 5 is a fragmentary view of the paper release bar and its associated ears for guiding the sides of the paper from the roll;

50 Figure 6 is a sectional view on the line 5—5 of Figure 5;

Figure 7, is a sectional view through the carriage;

Figure 8 is a section on the line 8—8 of 55 Figure 7;

Figure 9 is an elevation of the elements of the roll supporting means in disassembled position, and

Figure 10 is a sectional view of the roll, 60 on its spindle.

Referring now more particularly to the drawings, the carriage forming the subject matter of this invention is provided with a main supporting casting 1, having a depending portion 2 which supports a stud 3 on 65 which is loosely mounted a roll 4, said casting also supporting a second stud 5 on which is loosely mounted the roll 6, said rollers 4 and 6 forming bearings for a shaft 7 with which they contact, the shaft 7 being positioned in the rear of an adding machine as is customary. The upper face of the casting 1 is reduced in thickness at its forward edge providing a seat or track 8 throughout the length of the casting in which seats a 70 carrier 9 which is adapted to move laterally in said track. A second casting is provided which is secured to the carrier 9 by screws 75 10 or the like, said second casting being designated as 11 and as shown clearly in Figure 80 7, is positioned just above and parallel to the casting 1. Secured to each end of the casting 11 by means of screws 13 or the like are side plates 14, two in number, thus forming the carriage. To prevent accidental separation of the castings 1 and 11, and to maintain said castings in assembled position, retainers 15 are provided which are secured to casting 1 and extend upwardly adjacent the outer face of casting 11, the upper ends 85 of said retainers being bent over, forming flanges 16 which overlap the upper edge of casting 11, the ends thereof extending within the plane of the edges of the side plates 14, said extended ends forming limiting stops 90 for the carriage in its movement, as will be hereinafter described.

A platen shaft 17, supporting a platen 18 is loosely mounted in the side plates 14, the platen being capable of rotation through the 100 usual twirlers 19.

Pinned to a shaft 20 which is loosely

mounted in side plates 14 is an arm 21, which arm provides a carriage lock through the medium of a pin 22 which is so mounted in arm 21 as to engage within recesses 23 in casting 1 (see Fig. 2) or which may be withdrawn by means of a knob 24 whereby the carriage may be frictionally locked instead of positively locked by the pin engaging in the recesses. The shaft 20 has pinned to one end thereof an arm 25, carrying a finger piece 26, which arm is normally held in a rearward position by a spring 27, one end of said spring being attached to the arm 25 and the other to the carriage side plate 14 by a pin 27'. It will be obvious that by rocking the arm 25 forwardly the arm 21 will be lifted, thus lifting pin 22 out of a recess in the spacing bar from which position the casting 11 and its associated adjuncts can be moved laterally with relation to casting 1, this movement providing a columnar spacing for the paper.

Pinned to the platen shaft 17 adjacent one of the twirlers 19 is a ratchet 28, the teeth 25 of which are engaged by the detent roll 29 mounted on detent lever 30; lever 30 being pivoted at 31 to one of the side plates 14. The lever 30 is normally held in the position shown in Figure 4 by a spring 32 which has 30 one end connected to the lever and the other end connected to the side plate 14 at 32'. Pivoted to one end of the before mentioned shaft 7 is a feed lever 33 and from the other end of shaft 17 depends an arm 34. Shafts 35 and 36 are rigidly mounted between arm 34 and the lower end of feed lever 33. Pivoted to the upper end of feed lever 33 is a pawl 37 the end of which normally engages the teeth 40 of ratchet 28 because of spring 38 secured to said pawl and to side plate 14. Rocking of feed lever 33, will cause the pawl 37 to partially rotate the platen and establish the familiar line spacing for the paper, and for 45 this purpose the feed lever 33 is provided at its upper end with stop faces 39, 40 and 41. A projecting lip 42 at the end of a lever 43 is arranged to be moved into the path of the stop faces, and, contacting therewith will limit the rearward movement of the 50 pawl 37 and feed lever 33. As shown clearly in Figure 4, the lever 43 is pivotally mounted on the side plate 14 at 44 and one end thereof extends upwardly adjacent the side plate 14 and is retained in any desired 55 position by notches 45 of a plate 46 secured to plate 14. From the above it will be obvious that the stop 39 contacting with lip 42 will allow no backward movement of the 60 pawl 37; the stop 40 contacting with lip 42 will permit the pawl 37 to move backward a distance such that on its forward movement it will rotate the ratchet one tooth. Stop 41 will permit the rotation of the 65 ratchet two teeth. Thus means are pro-

vided for line spacing the paper, no space, single space, or double space as desired.

Mounted loosely in the side plates 14 is a shaft 47 which supports the pressure roll frames, each comprising two connected 70 swinging arms 48 supporting pressure rolls 49. The pressure rolls are normally held in contact with the platen 18 by means of springs 50, one end of each of which is secured to the connecting elements for the 75 swinging arms, and the other ends of each of which are secured to a shaft 51 rigidly secured between the side plates 14 at the rear thereof and relatively below the upper ends of the connected arms 48 (see Fig. 7). 80

Loosely mounted between the plates 14 and substantially parallel with the shaft 51 is a relatively rectangular shaft 52 having pinned to each end thereof a rock arm 53, substantially triangular in shape. The upper ends of connected arms 48 of the pressure rolls rest against this shaft 52 and limit the movement of the pressure rolls. The shaft 52 is normally held in elevated position by means of a spring 53', secured to one 90 of the rock arms 53 at 51' at one end and having its other end secured to the shaft 51 (see Fig. 2). Each rock arm 53 is provided with a stop projection 54 which abuts against a shaft 55 rigidly secured between 95 side plates 14 at the uppermost portion thereof.

From an inspection of Figure 7 it will be apparent that upon rocking of arms 53, the shaft 52 will be rocked forwardly, thus rocking the arms 48, supporting the pressure rolls, on their pivots and forcing the pressure rolls 48 away from their engagement with the platen. 100

Secured to and extending between the forward portions of rock arms 53 is a paper release bar 56 having secured thereto an upwardly extending, outwardly curved guide member 57 which is adapted to force paper coming thereagainst forwardly, thus preventing its becoming entangled with the mechanism of the machine. Also secured to said bar 56 by means of pins 58 or the like, and arranged in spaced relation to the before mentioned guide member 57 is a saw tooth cutting member 59 (see Figs. 1, 3 and 7). As will be apparent the paper passes between the saw tooth cutting member 59 and the guide member 57, the pins 58 serving as guide elements for the paper during 115 its passage. 120

The specific structure of the bar 56 is illustrated in Figures 5 and 6 wherein it can be seen that the rear face of bar 56 is provided with flanges 60 forming a guideway 125 for supporting paper guides 61 having portions 62 thereof arranged at substantially right angles and seating slidably in the guideways. The portions 62 of the guides or ears are provided with slots 63 through 130

which extend the ends of a flat spring 63' which springs serve to hold the guides in any desired position. A pin 65 is secured in the guideway for the purpose of accurately spacing the guide elements 61 in an obvious manner. Secured to the face of casting 11 and extending upwardly therefrom are two spaced arms 66 which are connected by arms 67 and 68. The arms 66 are each provided with hook shaped projections 69, 70 and 71, projections 70 and 71 being formed at the extreme ends of extensions formed integral and preferably a part of, the arms 66. The hook shaped ends are designated as 72, 73 and 74 respectively; 72 being positioned on shaft 20, 73 being mounted on shaft 47 and 74 being mounted on shaft 55. As shown in Fig. 2, the lower ends of arms 66 are flanged as at 74', screws 75' securing said arms to casting 11.

These arms 66 serve as a supporting means for a paper roll and its spindle as can be clearly seen in Figure 7 in which 75 indicates the paper roll. Pivotally secured to shaft 67 and extending rearwardly therefrom is a plate 76 which is normally held in elevated position by means of a spring 77, one end of which is secured to a depending arm 78 of the plate, the other end being secured to the bar 68, thus providing a brake for the paper roll as will be apparent. The upper portion of this plate 76 is provided with an extension 76' which serves as a stop and also a finger grip for said plate, stop 76' being adapted in certain positions to abut against the upper portion of one of the arms 66 before mentioned (see Fig. 2).

Particular attention is directed to the paper roll supporting element or spindle 79 which is clearly illustrated in Figures 8 and 9. The upper end of one of the arms 66 is provided with an interiorly screw threaded bearing 80 which receives the reduced threaded end of the spindle 79. Adjacent the threaded end of the spindle is an enlargement 81 which is received within the core 82 of the paper roll. Slidably mounted on the spindle 79 is a collar 83 which is received within the core 82 of the paper roll. The collar 83 is provided with a flange 84 adapted to be positioned against the paper on said roll as clearly shown in Figure 8, and secured to said flange 84 and preferably formed integral therewith is a lock element, 55 which in reality comprises a flange or collar 85, which latter is provided with a recess 86 in which is seated the arcuate portion of a spring 87. The flange 85 opposite the recess 86 is split, as shown at 88, and the remaining portion 89 of spring 87 is straight and bears against the spindle 79 as more clearly shown in Figure 10, and is adapted to be positioned within an annular recess 90 formed in the spindle 79.

With adding machines in use at the pres-

ent time, there are provided two standard widths of paper and should it be desired to use the wider width the collar 83 and its associated elements may be moved to the dotted line position shown in Figure 8, the 70 spring portion 89 engaging in recess 91 thus firmly retaining the paper roll in its desired position.

The opposite arm 66 of the paper supporting means is provided with an opening 92 at the end thereof, and the end of the spindle 79 is positioned therein. The opening 92, it can be seen, is of greater diameter than the spindle 79 but is substantially the same diameter as the enlarged end 93 of the 80 spindle adjacent the knurled button 94 secured to the end of the spindle. To replace a paper roll, the button 94 is turned thus unscrewing the spindle from the bearing 80. When the reduced end is free the spindle 85 may be tilted as shown in Figure 9, thus permitting the replacement of a roll as will be apparent.

As shown in Figure 7, in which the paper is designated as 95, said paper is fed from the roll between guides 62 which may be adjusted to accommodate the width of the paper used, the pressure rollers 49 and the platen, and then up between the pins 58, and between cutting member 59 and the paper 95 release bar 56, then up in front of the guide member 57 which forces the paper forwardly and prevents its entanglement with any of the mechanism.

It is believed that the operation of this device will be apparent from the above description, taken in conjunction with the drawings but I desire it to be understood that the drawings are for illustrative purposes only and that various changes in the form and proportions of the device may be made within the scope of the appended claims without departing from the spirit of the invention.

Having thus described my invention, what I claim and desire to secure by U. S. Letters Patent is:

1. In an adding machine carriage having supporting castings, side frames, a platen, and paper roll holding means, a plurality of pressure rolls engaging said platen, a substantially rectangular shaft for pivotally mounting said rolls, a loosely mounted shaft secured between the side frames, and adapted upon rotation to release the pressure rolls from engagement with the platen, rock arms secured to said shaft, and a paper release bar secured to said rock arms.

2. In an adding machine carriage having supporting castings, side frames, a platen, and paper roll holding means, a plurality of pressure rolls engaging said platen, a shaft for pivotally mounting said rolls, a loosely mounted shaft secured between the side frames, and adapted upon rotation to

release the pressure rolls from engagement with the platen, rock arms secured to said shaft, and a paper release bar secured to said rock arms and carrying slidable paper guides 5 and a paper cutting element.

3. In an adding machine carriage having a platen, pressure rolls, and paper roll supporting means, a fixed casting having a guideway therein, a movable casting 10 mounted above said fixed casting and a guide element secured to said movable casting and positioned in said guideway, said movable casting supporting the elements of the carriage.

15 4. In an adding machine carriage having supporting castings, side plates, a platen, pressure rolls for said platen, and a paper roll holder, a bar secured between said side plates and movable to release said pressure 20 rolls, a rock arm secured to each end of said bar, a paper release bar secured to said rock arms, and paper guides secured to said paper release bar.

25 5. In an adding machine carriage having supporting casting, side plates, a platen, pressure rolls for said platen, and a paper roll holder, a bar secured between said side plates and movable to release said pressure rolls, a rock arm secured to each end of 30 said bar, a paper release bar secured to said rock arms and provided with a guideway on its inner face, paper guides positioned and movable within said guideway, and means 35 including a pin for accurately spacing said guides.

6. In an adding machine carriage having supporting castings, side plates, a platen, pressure rolls for said platen, and a paper roll holder, a bar secured between said side 40 plates and movable to release said pressure rolls, a rock arm secured to each end of said bar, a paper release bar secured to said rock arms and provided with a guideway on its inner face, paper guides positioned and 45 movable within said guideway, means including a pin for accurately spacing said guides, and means secured to the outer face of said paper release bar for forcing the paper in a forward direction.

50 7. In an adding machine carriage having supporting castings, side plates, a platen, pressure rolls for said platen, and a paper roll holder, a bar secured between said side plates and movable to release said pressure 55 rolls, a rock arm secured to each end of said bar, a paper release bar secured to said rock arms and provided with a guideway on its inner face, paper guides positioned and movable within said guideway, means including 60 a pin for accurately spacing said guides, a guide element secured to the outer face of said paper release bar and adapted to force the paper in a forward direction, and a paper cutting element secured to said paper 65 release bar.

8. In an adding machine carriage having supporting castings, side plates, a platen, pressure rolls for said platen, and a paper roll holder, a bar secured between said side plates and movable to release said pressure 70 rolls, a rock arm secured to each end of said bar, a paper release bar secured to said rock arms and provided with a guideway on its inner face, paper guides positioned and movable within said guideway, means 75 including a pin for accurately spacing said guides, a guide element secured to the outer face of said paper release bar and adapted to force the paper in a forward direction, and a paper cutting element secured to said paper release bar, between which and said guide element the paper is received and guided.

9. As an element of an adding machine carriage, a paper release bar having a guideway on its inner face.

10. As an element of an adding machine carriage, a paper release bar having a guideway on its inner face, and guide elements 90 secured and movable therein.

11. As an element of an adding machine carriage, a paper release bar having a guideway on its inner face, guide elements secured and movable within said guideway, and resilient means secured to said elements for 95 retaining the same in the desired position.

12. As an element of an adding machine carriage, a paper release bar having a guideway on its inner face, guide elements secured and movable within said guideway, spring 100 means for retaining the same in desired positions, and means comprising a pin for accurately spacing said guide elements in one position.

13. In an adding machine carriage, the combination of a frame, a platen, pressure rolls for said platen, means for releasing the pressure rolls from said platen, a paper release bar connected with said pressure roll releasing means, of an adjustable paper roll 105 holder and guides.

14. As an element of an adding machine carriage, a paper roll holder comprising spaced supporting arms, a bearing in one of said arms, a spindle secured between said arms and adapted to have one end thereof secured in said bearing, a fixed protuberance on said spindle near one end thereof and a collar slidable on said spindle and adapted to be retained in a plurality of fixed 110 positions as desired, on said spindle whereby paper rolls of varying widths may be accommodated.

15. A carriage for an adding machine or the like, comprising, a fixed casting, a slideable casting adjacent to said fixed casting, a side piece secured to each end of said slideable casting, shafts secured to and extending between said side pieces, a platen roll secured to one of said shafts, a plurality of 115 120 125 130

pressure rolls pivotally secured to one of said shafts, a shaft loosely secured between said side plates and controlling the movement of the pressure rolls, a rock arm secured to said loosely mounted shaft, a paper release bar secured to said rock arms, paper guides slidably secured to said paper release bar, a paper cutting element secured to and spaced from said paper release bar, the spac-

ing elements therefor forming paper guides 10 and means secured to certain of the before mentioned shafts for supporting a paper roll.

5 In testimony whereof, I have signed my name to this specification this seventeenth 15 day of August, 1923.

NELSON WHITE.
